UNITED STATES PATENT OFFICE.

WILLIS O. PROUTY, OF HERMOSA BEACH, CALIFORNIA, AND WALTER A. SCOTT, OF RIVER FOREST, ILLINOIS.

PROCESS OF MAKING PHONOGRAPHIC RECORDS.

Application filed March 25, 1926. Serial No. 97,327.

The purpose of our invention is the provision of means for making phonographic records in the form of long strips or tapes with the record extending longitudinally thereof, the material of the strip or tape sufficiently flexible to be wound on a reel. The fact that a flexible tape would afford means for making phonographic records of great length has been perceived heretofore, but the production of such a record involves difficulties not encountered in the production of the disc records now used. We have invented a simple and economical method of producing such records. In brief we first make a record in a helical line upon the outer surface of a hollow, thin cylinder of celluloid or material having similar properties. The pitch of the helix which the record follows is made sufficiently great to leave a substantial space between successive turns of the record line. After the completion of the cylindrical record we cut the record along a helical line, the line of the cut running between the successive turns of the previously formed record line, thus producing the record in the form of a strip the length of which is dependent only on the diameter and length of the cylinder upon which it was originally produced. Instead of producing a single record line upon the strip or tape a plurality of record lines may be formed side by side and comparatively close together, the pitch of the helical path of the record lines being sufficiently great to leave sufficient cutting space between the successive turns of the group of record lines.

In the drawing:

Figure 1 is a side view of a hollow cylinder of celluloid or material of similar properties having two record lines in helical form indicated thereon, and the intervening cutting lines also shown.

Figure 2 is a view of a section of the strip or tape formed by cutting the cylindrical record shown in Figure 1 along a helical line.

Methods have heretofore been devised and used to a considerable extent wherein thin, hollow cylindrical records have been formed by expanding a hollow celluloid cylinder, or cylinder of some similar material, within a hollow cylindrical matrix bearing the phonographic record on its inner surface. These matrices have been formed by electro-depo-

sition of metal upon the surface of a cylindrical wax record and then backing the thin electro-deposit with a substantial layer of metal. This part of the procedure is old and forms no part of our invention, nor does the procedure followed in expanding the blank celluloid cylinder within the matrix to impress the record thereon. A method heretofore used for expanding the celluloid cylinder in the matrix consists in closing the ends of the cylinder steam-tight while in position within the matrix and then injecting into the interior of the cylinder steam under sufficient pressure to produce the desired result. The heat of the steam softens the material sufficiently to cause it to receive from the matrix the impression of the record and the pressure causes the outer surface of the cylinder to establish such intimate contact with the matrix that the impression of the record is an exact reproduction. Upon cooling, the cylinder contracts sufficiently to permit its withdrawal from the matrix. The details of this part of the procedure being old need not be further described here.

In Figure 1 we show a cylinder bearing two record lines side by side, which lines may represent either separate records or successive parts of a single record to be reproduced continuously by reversing the direction of movement of the tape under the reproducing needle when the end of the tape is reached. This cylinder may be formed by the procedure above referred to or by any other suitable method such as flowing a temporarily liquefied material over the interior of a hollow cylindrical matrix. After being so formed the thin cylindrical record is cut along the helical line indicated by the numeral 3, thus converting the record into the form of the tape shown in Figure 2 with the record lines 1, 2 extending longitudinally thereof.

The above described methods of producing thin cylindrical records are applicable to the production of cylinders of large diameter and great length, thereby rendering it possible by our improved method to produce continuous tape records of great length.

We claim:

1. In a process of the class described the operation of forming a phonographic record in a helical line on the surface of a cylinder and then cutting from said cylinder a heli-

cal strip bearing said record in a line extending longitudinally thereof.

2. In a process of the class described the operation of forming a phonographic record in a helical line on the exterior surface of a hollow cylinder of flexible material, and then severing said cylinder along a helical line lying between the successive turns of

the helical record line and thereby producing a record in the form of a strip having 10 the record line extending longitudinally thereof.

In testimony whereof, we have subscribed our names.

WILLIS O. PROUTY.
